CONVERTIBLE CRIB

Earl F. Hamilton, Columbus, Ind., assignor to Hamilton Cosco, Inc., Columbus, Ind., a corporation of Indiana

Continuation of applications Ser. No. 59,030, Jan. 13, 1960, and Ser. No. 59,031, Jan. 13, 1960. This application June 22, 1961, Ser. No. 65,688

Term of patent 14 years

(Cl. D5—5)

FIG. 1 is a perspective view of a convertible crib showing my design as a crib provided with solid side and foot panels;

FIG. 2 is a perspective view of the convertible crib design shown in FIG. 1, but showing one of the side walls thereof in lowered position;

FIG. 3 is a perspective view of the convertible crib design shown in FIG. 1, but showing the same as a youth bed;

FIG. 4 is a perspective view of the convertible crib design shown in FIG. 1, but wherein the side rails and foot members are all formed from tubular stock;

FIG. 5 is a perspective view of the convertible crib design shown in FIG. 4, but showing one of the side walls thereof in lowered position; and

FIG. 6 is a perspective view of the convertible crib design shown in FIG. 4, but showing the same as a youth bed.

The essential features of my design reside in the arrangement of the collapsible side walls in combination with the solid headboard and open mesh end member together with the outward angle on the leg supports, all as shown.

This application is a continuation of my copending applications Serial No. D. 59,030, filed January 13, 1960, and Serial No. D. 59,031, filed January 13, 1960, now abandoned.

I claim:

The ornamental design for a convertible crib as shown and described.
